UNITED STATES PATENT OFFICE.

GEORGE E. PANCOAST, OF BROOKLYN, NEW YORK, ASSIGNOR TO AMERICAN LITHOGRAPHIC COMPANY, A CORPORATION OF NEW YORK.

PRINTING-PRESS.

SPECIFICATION forming part of Letters Patent No. 793,022, dated June 20, 1905.

Original application filed January 29, 1900, Serial No. 3,170. Divided and this application filed December 22, 1904. Serial No. 237,951.

To all whom it may concern:

Be it known that I, GEORGE E. PANCOAST, a citizen of the United States, and a resident of Brooklyn, in the county of Kings and State of New York, have invented certain new and useful Improvements in Printing-Presses, of which the following is a specification.

My invention relates to printing-presses, and while as to some of its features it is not confined to any particular method of printing or to any particular type of press it more especially relates to presses employing planographic design-surfaces, and more particularly to that type of such presses in which a plurality of design-cylinders carrying planographic surfaces are arranged to print in registry upon paper or similar material in substantially instantaneous succession.

It is necessary or desirable that rotary multi-color-presses designed for executing the finer grades of work, and particularly those employing planographic design-surfaces, be so constructed that the inking-rollers and the damping-rollers also, where damping-rollers are employed, may at will be brought into and out of operative relation with the respective design-cylinders, and also that the design-cylinders may at will be brought into and out of operative relation with the impression surface or surfaces, as when the press is stopped or when it is desired for any reason to suspend the printing operation. It is also necessary or desirable that such presses be constructed with ample provision for distribution of the ink and the damping fluid also, where damping fluid is employed, and that ample provision be made for accurate regulation of the supplies of the ink and the damping fluid. It is also necessary or desirable that the various rollers of the inking and damping mechanisms be reliably held in proper contact with each other, and particularly that the rollers which apply the ink and damping fluid to the design-surfaces be held in proper operative relation therewith.

An object of my invention is to provide a construction whereby the several operations

or features referred to may be realized in a practical way.

More specifically, my invention has for an object to provide a construction whereby the inking mechanism and the design-cylinders may at will be readily brought into or out of operative relation with little disturbance of the inking mechanism as a whole; also, to provide a construction whereby the design-cylinders and the impression mechanism also may at will be readily separated or brought together with little disturbance of the mechanism considered as a whole; also, to provide a construction of inking mechanism which will insure thorough distribution of the ink and thorough application thereof to the design-surfaces; also, to provide a construction of inking mechanism whereby the various ink-distributing and ink-applying rollers are reliably held in proper contact with each other and with the design-surfaces and whereby frequent or accurate individual adjustment of the several rollers is rendered unnecessary; also, to provide a construction of inking mechanism whereby the inking mechanism may be placed in a press in various positions with little disturbance or adjustment of the operative relations of the parts; also, to provide a construction of inking mechanism which is self-contained, and when a plurality of them are combined in a single machine to make them interchangeable, and to provide a simple and efficient operating means common to all or to a plurality of the inking mechanisms for bringing them into or out of operation and which will enable any one or more of them to be disconnected.

It is also an object of my invention to provide a construction of damping mechanism whereby the damping-rollers and the design-cylinders may at will be readily brought into or out of operative relation; also, to provide a simple and efficient operating means common to all or a plurality of the damping mechanisms, whereby the damping mechanisms may be brought into or out of operation together with the inking mechanisms and with

the design-cylinders; also, to provide a damping mechanism which is self-contained and simple in construction and reliable in operation and which does not require frequent or accurate individual adjustment of the various rollers, and in which the supply of damping fluid can be accurately adjusted and reliably maintained.

It is also an object of my invention otherwise to improve the machine and the several parts thereof and the means for operating and controlling the same and to simplify and cheapen and render more practicable the use of multicolor-printing presses for the production of the finer classes of work.

With these and other objects in view my invention consists in the novel parts, improvements, and combinations herein shown and described, in so far as the same do not form the subject-matter of any prior application, Serial No. 3,170; of which this application is a division.

The accompanying drawings, which are referred to herein and form a part hereof, show one embodiment of my invention and the several features thereof, the machine illustrated being a multicolor press employing planographic design-surfaces and printing six colors upon a web of paper.

Of the drawings, Figure 1 is a side elevation of a machine embodying my invention. Fig. 2 is a longitudinal section of the same, taken on the line 2 2 of Fig. 3. Fig. 3 is a transverse section of the same, taken on the line 3 3 of Fig. 2. Fig. 4 is an elevation, on an enlarged scale, of one of the inking mechanisms as viewed from the side of the machine illustrated in Fig. 1. Fig. 5 is a sectional view of the side of the inking mechanism illustrated in Fig. 4, the section being taken on the line 5 5 of Fig. 4. Fig. 6 is an elevation of one of the inking mechanisms as viewed from the side of the machine opposite to that illustrated in Fig. 1. Fig. 7 is a sectional view of the side of the inking mechanism illustrated in Fig. 6, the section being taken on the line 7 7 of Fig. 6. Figs. 8 and 9 are sectional elevations, on a still larger scale, illustrating certain parts of the inking mechanisms in different positions, the section in each case being taken on the lines 8 8 of Fig. 5 and looking in the direction of the arrow. Figs. 10 and 11 are sectional details, taken on the lines 10 10 and 11 11 of Figs. 8 and 9, respectively. Figs. 12 and 13 are respectively a side elevation and transverse section of a detail. Fig. 14 is an end view of the ink-supplying part of the inking mechanism. Fig. 15 is a plan view of the same. Fig. 16 is a view of the end of the same opposite to that illustrated in Fig. 14. Figs. 17 and 18 are sectional views, taken at right angles to each other, illustrating details of the same. Fig. 19 is a sectional elevation illustrating a means for supporting and operating the damping mechan-

isms, the design-cylinders and inking mechanisms being illustrated diagrammatically. Fig. 20 is an end elevation of one of the damping mechanisms on an enlarged scale. Fig. 21 is a broken side elevation illustrating the end of 70 the damping mechanism appearing in Fig. 20. Fig. 22 is an elevation of the end of the damping mechanism opposite to that shown in Fig. 20. Fig. 23 is a broken side elevation of the same. Figs. 24 to 31, inclusive, are detail views illustrating various features of the damping mechanism. Fig. 32 is a sectional elevation of the damping mechanism, taken on the line 32 32 of Fig. 21 and looking in the direction of the arrow. Fig. 33 is a similar view illustrating 80 the applying part of the damping mechanism in a different position. Figs. 34 to 37, inclusive, are sectional views illustrating various details of the damping mechanism.

Like reference-numbers indicate the same parts wherever they occur throughout the several views.

Referring now in detail to the particular embodiment of the invention illustrated in the drawings, 1 represents an impression-cylinder mounted upon a shaft 2, journaled in suitable bearings 3 and 4, carried by the main side frames 5 and 6. Any suitable impression mechanism may be employed. Where the machine is designed to print upon a web, as 95 in the particular embodiment shown, an impression-cylinder is preferably employed, and the cylinder is provided with a substantially circumferentially continuous impression-surface 7 of suitable material, such as paper or 100 rubber composition, or both. The impression-cylinder may be driven in any suitable way. As shown, it is provided with a ring-gear 8, secured to one end thereof and connected to any suitable source of power by a train of 105 driving-gears 9.

The material to be printed upon may be supplied to the impression mechanism in any suitable form. In the construction shown the paper is supplied in the form of a web 12, 110 which is led from a supply-roll around a tension device consisting of a roller 13, yieldingly and adjustably supported by springs 14, which are mounted upon guiding and adjusting rods. From the tension device the paper is led to a 115 guide-roller 16. Then after passing around the impression-cylinder the web is guided by a series of disks 17 to a cutting mechanism 18, where it is severed into sheets which pass to a delivery device 19, including a pair of endless chains 20, having suitable grippers for carrying the sheets to a receiver. (Not shown.) The devices for manipulating the paper form no part of my present invention and need not be further described.

So far as some of the features of my invention are concerned any suitable character of design-surface may be employed. As to its main features, however, the invention is particularly useful as embodied in machines em- 130

ploying planographic design-surfaces. Where the machine is designed to print on a web, the design-surfaces are preferably cylindrical and circumferentially continuous, and they are preferably formed on hollow shell-like tubular structures adapted to be removably and replaceably mounted upon cylindrical supports. In the particular machine illustrated in the drawings the design members are planographic, and they consist of thin shell-like tubes 21, removably and replaceably mounted on cylindrical supports 22, carried by shaft 23, journaled in boxes 24 and 25.

In accordance with one feature of my invention suitable means are provided whereby the design-cylinders and the impression mechanism may at will be readily separated or brought together, so that when the machine is stopped or the printing operation suspended the design-surfaces may be supported out of contact with the impression surface or surfaces as required to coat them with the gum used on lithographic or planographic surfaces to preserve the ink-repelling qualities of the non-printing portions. In the particular construction shown the boxes 24 and 25, which support the design-cylinders, are slidably mounted in radial guideways 26 and 27, formed in the frame of the machine, and they are connected to radially-arranged sliding bars 28 and 29, suitably guided on the frame. The sliding bars 28 and 29 at the opposite sides of the machine are operated or controlled by a pair of rings 30, which are mounted on disks 31 and 32, suitably journaled on the side frames of the machine in concentric relation with the shaft 2 of the impression-cylinder 1. Each of the bars 28 and 29 is provided with a stud 33, which engages an elongated cam slot or groove 34 in the corresponding ring 30.

In the particular embodiment of the invention illustrated the cam-slots 34 are of the same length, and they are arranged in spiral-like or eccentric relation to the axis of the rings, and they are spaced at angular distances from each other corresponding to the spacing of the design-cylinders around the impression-cylinder, so that when the ring-bearing disks 31 32 are rotated for a suitable distance in opposite directions the radial bars, together with the design-cylinders connected thereto, will be moved inwardly or outwardly, depending on the direction of the rotation of said disks. Each of the radial bars is preferably engaged at its inner end by a stiff spiral spring 33', which springs press the bars radially outward and serve to avoid lost motion between the pins and the cam-grooves. Any suitable means may be provided for operating the disks 31 32 and with them the rings 30 in unison. As shown, said disks are provided with gear-segments arranged to mesh with pinions fixed near the opposite ends of a cross-shaft 35, suitably journaled in the side frames and driven in opposite directions from

any suitable source of power by a train of gears 36.

Any suitable means may be provided whereby the pressure with which each of the design-cylinders bears upon the impression-cylinder may be independently varied. As shown, the sliding bars 28 and 29 are connected to the boxes 24 and 25 at the opposite ends of the design-cylinders by means of adjustable connections 37 and 38, the connections 37 being pivotally connected to the bars 28 and removably connected with the boxes 24 by nuts 39 and 40 to permit the design members to be removed from the design-cylinders and new ones substituted therefor.

The means whereby the design-cylinders of the particular machine illustrated in the drawings are supported and whereby provision is made for the removal and replacement of the design members is effected forms no part of my present invention, and they will therefore not be further described herein. The design-cylinders may be driven in any suitable way. As shown, each of them is provided with a gear 53, secured to a fixed collar 50, preferably by means permitting circumferential adjustment of the cylinder with relation to its gear. As shown, the gears 53 are engaged and driven by a gear 54, fixed to the impression-cylinder 1.

The machine is provided with an inking mechanism for each of the design-cylinders, and where planographic design-surfaces are used the machine is also provided with a damping mechanism for each planographic design-surface.

In the particular embodiment of my invention illustrated in the drawings the several inking mechanisms are substantially the same in construction. A description of one of them, together with the description of the means whereby the several inking mechanisms are driven and controlled, will be sufficient. The inking mechanism in its preferred form may for convenience be described as consisting, primarily, of four parts—viz., a supplying part for supplying the ink in regulated quantities, a distributing part for thoroughly breaking up or distributing the ink, an applying part for applying the distributed ink to the design-surface, and a conveying part for carrying the ink from the distributing part to the applying part. While the applying and conveying parts of the inking mechanism incidentally form branches or continuations of the distributing part, their main functions are to transfer the ink from the distributing part and apply it to the design-surfaces, the distributing part of the inking mechanism being of such a character as to thoroughly distribute the ink independently of the other parts of the inking mechanism, and it is to be understood that my invention in its broader aspects is not confined to the employment of means corresponding to each of

the parts into which the particular construction shown has for convenience of description been divided.

Referring now to the drawings, and more particularly to Figs. 4 to 9, inclusive, it will be observed that the larger portion of the inking mechanism is mounted in an auxiliary frame consisting of the side pieces or brackets 60 61, fixed to and practically forming a continuation of the main side frames of the machine.

So far as some of the features of my invention are concerned any suitable ink-distributing mechanism may be employed. In accordance with the embodiment shown of one feature of my invention the distributing part of the inking mechanism consists of a plurality of hard rollers 63, 64, 65, 66, and 67, preferably of metal, mounted in suitable bearings in the frames 60 and 61. A soft roller 68 is yieldingly held in contact with each two adjacent hard rollers 63 and 64, 64 and 66, 63 and 65, and 65 and 67, as shown, there being formed by this arrangement a double series of hard and soft rollers arranged alternately.

In accordance with one feature of my invention the contacts between the adjacent rollers are maintained by a yielding force, the means for yieldingly holding the rollers preferably acting on the rollers individually and being such as to compensate effectively for variations in the diameters of the rollers, whereby frequent or accurate individual adjustment of the rollers is rendered unnecessary. The means whereby the rollers are yieldingly held may be greatly varied in construction. The means shown consists of journaled boxes 69, one at each end of each roller, said boxes being loosely guided between the frames 60 61 and the heads of bolts or pins 70, the shanks of which pass through suitably-enlarged perforations in the boxes, as indicated in dotted lines. Each bearing is further guided by a rod 71, pivoted at one end to the frame and passing through a guide extension 72 of the bearing 69 and terminating in a guide-opening formed in the bearing in line with the opening in the extension 72. The end of each rod nearest the bearing is threaded and provided with an adjusting-nut 73, between which and the inner end of the guide extension 72 is confined a compression-spring 74. Each of the rods 71 being pivoted at its other end to a fixed part of the frame, the compression-spring tends to draw the bearing 69 inwardly and with it the roller carried thereby. By reason of the universal manner in which the bearings 69 are supported and guided the tension-springs 74 tend to keep the rollers 68 constantly in contact with the adjacent hard rollers, and this contact will be maintained irrespective of the position of the inking mechanism in the press and irrespective of the inking mechanism 65 with respect to the action of gravity on its

various rollers. This construction also possesses the further advantage that inaccuracies or irregularities in the settings or adjustments and in the diameters of the rollers are effectively compensated for. In other words, it is not necessary that the rollers be adjusted with great accuracy or that they be frequently adjusted individually. All that is required in the way of individual adjustment of the rollers is adjustment of the compression of the springs 74.

In order that the rollers may be readily removed and replaced, the bearings 69 are provided with hinged sections 75, which are held in place by pivoted bolts 77, carrying thumbscrews 76. The hard rollers 63, 64, 65, 66, and 67 are preferably driven positively. This may be accomplished by any suitable means. As shown, the shafts of said rollers are provided on the outside of the frame 61 with gears 83, 84, 85, 86, and 87, respectively. These gears are driven from a shaft 88, which constitutes the main driving-shaft or power center, from which are driven all parts of the inking mechanism not driven frictionally by contact with the design-surface. As shown, the shaft 88 is driven from the gear 89, mounted on a pin 90, carried by a bracket 91, fixed to the side frame 6 of the machine, motion being conveyed from the gear 89 by a train of gears 92, 93, and 94, the last of which is fixed on the end of the shaft 88. The intermediates 92 and 93 are preferably carried by a pair of links 95 and 96, as shown, this construction avoiding the use of long studs 100 projecting from the side frames and affording ready access to the outer part of the design-surface besides forming a rigid and efficient support for the gears.

The gears 89 for all the inking mechanisms 105 mesh with and are driven by a large gear 97, mounted concentrically with the impression-cylinder, preferably by being fixed to and driven by the shaft 2. In the particular construction shown the gear 97 thus constitutes 110 a common actuating part for all the inking mechanisms and acts to drive them independently of the design-surfaces and independently of the damping mechanism. The shaft 88 carries a gear 100, which meshes with the gears 115 84, 85, 86, and 87 and drives the gear 88 through the gear 84, and a pinion 101, mounted on a fixed stud. The gear 100 and the pinion 101 are made wider than the gears with which they mesh to allow for the endwise reciprocation or vibration of the rollers to which the latter gears are fixed.

Any suitable means may be provided for vibrating the rollers. In accordance with one feature of my invention, however, the corresponding hard rollers of the two series are connected in pairs and vibrated in unison. The particular embodiment of this feature of my invention illustrated in the drawings is shown in detail in Figs. 6 and 7. In accord- 130

ance with this construction the shaft 88 is extended through the frame 60 and is provided at its end with a pinion 102. The pinion 102 meshes with a gear 103, the motion of which by means of beveled gears 104 and 105 is communicated to a shaft 106, arranged at right angles to the shaft 88 and provided with two oppositely-arranged cranks 109 110 between the brackets 107 108 and a crank 111 at its end beyond the bracket 108. The crank 109 engages a slot in a cross-head 112, carried by and located between fixed collars on the shafts of rollers 66 and 67, and this causes these two rollers to vibrate in unison. The crank 110 is similarly connected with the rollers 164 165 by cross-head 113. The crank 111 is connected by a pitman 114 to a sliding head 115, confined between collars on the end of the shaft of the roller 63. This construction, it will be observed, forms a simple, strong, and compact mechanism for vibrating the various rollers of the distributing part of the mechanism. By the arrangement of the rollers in a plurality of series and the vibration in opposite directions of the opposite rollers of each series the flow of ink is divided into a plurality of streams and each stream is independently and thoroughly distributed, thus insuring an even and uniform application of the ink to the design-surfaces. The ink is applied to the design-surfaces by a plurality of soft applying-rollers 120. The applying-rollers, as well as the other soft rollers of the inking mechanism, should be provided with surfaces of a material adapted to the particular class of design-surfaces with which the inking mechanism is employed. With planographic design-surfaces the soft rollers usually consist of a soft inner or basic portion, as rubber or suitable fibrous material, and an outer covering of leather or felt or other suitable soft material.

The ink may be communicated from the distributing part of the inking mechanism to the applying part thereof in any suitable way. In accordance with one feature of my invention and with the particular embodiment thereof illustrated an intermediate or conveying part is provided for this purpose. As shown, the conveying part consists of a rider-roller 121, yieldingly held in contact with a pair of the applying-rollers, and a roller 122, yieldingly held in contact both with a roller of the distributing part of the inking mechanism and with the rider-roller 121. The means for yieldingly holding the rollers 121 122 will be presently described.

It is desirable, especially where planographic design-surfaces are employed, to separate the design-surface and the applying-rollers when the machine is not in operation to prevent injury to the design-surface and to the applying-rollers, which would result from allowing them to remain long in pressure-contact when not in motion. In accordance with

one feature of my invention this is accomplished by separating and bringing together the design-surface and the applying-rollers without disturbing the other parts of the inking mechanism as a whole. In accordance 70 with the embodiment illustrated of this feature of the invention the applying-rollers 120 are mounted in auxiliary frames 123, pivoted to the frame of the machine by bolts 124 and connected to suitable operating means, so 75 that they may be moved about their pivots to carry the applying-rollers into or out of operative position with relation to the design-surface without moving the inking mechanism as a whole. 80

As shown, there are two pivotally-arranged frames 123, pivoted at opposite sides of the design-cylinder and each carrying a pair of applying-rollers. The means shown for controlling and actuating the pivoted frames consists of a pair of rock-shafts 125 126, each extending transversely through the machine and connected near its opposite ends with a pair of the frames 123, carrying the opposite ends of a pair of the applying-rollers 120, the 90 shaft 125 being connected with the frames 123 at one side of the design-cylinder by means of arms 127 and links 129 and the shaft 126 being connected with the frames at the opposite sides of the design-cylinder with pairs of 95 arms 128 and links 130. Any suitable means may be provided for operating the shafts 125 and 126. The means shown will be presently described. 100

In accordance with one feature of my invention the applying-rollers are yieldingly held in contact with the design-cylinder when in operative position, said means being adapted to compensate effectively for variations in the diameters of the rollers and also to hold 105 said rollers in operative position irrespective of the gravity relation between said rollers and the design-cylinder. This holding means may be widely varied in construction. As shown, the applying-rollers are mounted in 110 journaled boxes 131, slidably supported in the frames 123 and pressed toward the design-cylinder by compression-springs 132, confined between the boxes 131 and adjacent nuts 133, mounted on guide-studs 134. The rider-rollers 121, which are preferably hard-surfaced rollers, are yieldingly held in contact with the two adjacent applying-rollers 120 by means of bearings 135, slidably mounted on pivot-bolts 137, having elongated openings indicated in dotted lines, rods 138 also pivoted on the bolts 137 and passing through openings in lugs 139, formed on the bearings 135, the outer ends of the rods 138 being threaded and provided with adjusting-nuts 140, between 120 which and the lugs 139 are confined compression-springs 141. By reason of this construction the riders will be yieldingly held in contact with both adjacent applying-rollers under the same pressure. 130

The rollers 122, which are preferably soft rollers, are, in accordance with the construction shown, mounted in bearings 145, slidably mounted and guided on rods 146, which are pivoted concentrically with the rollers 66 and 67. The outer or free ends of the rods 146 are threaded and provided with adjusting-nuts 147, between which and the inner ends of the bearings 145 are confined compression-springs 148. By reason of this construction the rollers 122 will always be held in yielding contact with the rollers 66 and 67 irrespective of such variations in the diameters of the rollers as are liable to and do occur from time to time by reason of shrinkage or swelling or wear of the rollers and also irrespective of the gravity relations between these rollers.

For the purpose of permitting the applying-rollers to be moved into and out of operative relation with the design-surface and to maintain a constant connection between the applying-rollers and the distributing part of the inking mechanism irrespective of the position of the applying-rollers the rollers 122 are preferably also yieldingly held in contact with the rider-rollers 121. This may be accomplished by any suitable means. As shown, compression-springs 150 are used, the same being confined between pivot-blocks 151, connected to the bearings 145, and pivot-blocks 152, pivotally mounted on the frame, as clearly shown in Fig. 10, suitable adjustment being provided to vary the tension of the springs 150. It will be understood that each of the rollers is provided at each end with yielding holding means of the character described and shown in Figs. 8 to 11. Each of the holding means is also constructed to permit ready removal of the rollers from the machine when desired.

Referring now to the particular means illustrated for operating the shafts 125 and 126, (see Figs. 1 and 3,) it will be observed that said shafts are geared together near one end by suitable pinions or segments 155 156, so as to cause them to rotate in opposite directions in unison. As shown, the shaft 126 of each of the inking mechanisms is provided with an arm 157, said arm being preferably adjustably connected with the shaft by means of a bolt 158, engaging a slot 159 in the arm. The arms 157 of the adjacent inking mechanisms are connected together by links 158', each of which is preferably and as shown made adjustable in length.

So far as some of the features of my invention are concerned any suitable means may be employed for actuating the several shafts 126 in unison. As shown in Fig. 1, the arms 157' on the shafts 126 of the two lower inking mechanisms are connected to an arm 159 by links 160, and the arm 159 is suitably pivoted on the lower part of the frame and is connected to one of the segment-disks 32 by

a pin 162, fixed on the segment and engaging a slot 163 in the arm. By reason of this construction whenever the segment 32 is moved to carry the design-cylinders into or out of operative relation with the impression-cylinder the applying-rollers of the inking mechanisms will be also moved into or out of operative relation with the design-cylinders. By reason of the adjustments described the applying part as a whole of each of the inking mechanisms may be adjusted independently of the other applying parts, so as to bring them into proper operative position with the corresponding design-cylinder, but when once adjusted will require little or no further attention by reason of the means for yieldingly holding the applying-rollers in operative position. By reason of the means for yieldingly holding the various rollers of the several inking mechanisms in contact, moreover, frequent or accurate individual adjustment of the rollers will be rendered unnecessary.

So far as some of the features of my invention are concerned any suitable mechanism may be provided for supplying ink to the ink-distributing mechanism. In accordance with one feature of my invention, however, the ink-supplying part includes an ink-fountain and a ductor-roller and means for supporting and operating the same so constructed that the fountain may be arranged in a level position irrespective of the position of the inking mechanism in the press. In accordance with the particular embodiment of this feature of my invention illustrated (see Figs. 1, 2, and 12 to 18, inclusive,) the ink-supplying part comprises a fountain 165, in which is mounted for rotation a fountain or ductor roller 166. Arranged above the fountain and in contact with the ductor-roller is a ductor-blade 167 of the usual construction and with the usual means for varying the pressure thereof on the ductor-roller, so as to vary the amounts of ink delivered from the fountain. The ink is transferred from the fountain-roller to the first roller 63 of the distributing mechanism by a ductor-roller 168, the fountain-roller being moved intermittently and the ductor-roller being moved first into contact with the fountain-roller and then into contact with the roller 63.

In order that the fountain may be arranged in a level position irrespective of the position of the inking mechanism in the press without deranging the operative relation between the fountain-roller and the ductor-roller and between the ductor-roller and the distributing-roller, the fountain and ductor are made adjustable together as a unit with relation to the rest of the inking mechanism. This is accomplished by mounting the fountain and ductor, together with their operating mechanisms, on an auxiliary frame consisting of side pieces 169 and 170, pivotally mounted in con-

centric relation with the roller 63 and rigidly connected together by the fountain 165, as shown in Fig. 15. The fountain-roller 166 shown consists of a short shaft 175, (see Fig. 18,) mounted in a frame 170 and connected by a clutch 176 with the shaft of the fountain-roller, so that the fountain-roller may be readily removed when desired. The shaft 175 carries a ratchet-wheel 177, which is engaged by a pawl 178, carried by an arm 179, loosely pivoted on the end of the shaft 175.

To regulate the distance through which the fountain-roller is turned on each operation of the pawl, a guard-cam 180 is provided, the same being loosely mounted on the shaft 170 and held by an arm 181, having a spring-detent 183, adapted to engage a notched segment 182, fixed on the frame 170. The pawl-carrying arm 179 is oscillated by a crank-pin 184, carried on the cam-disk 185 through a connecting-rod 186. The cam 185 is carried by a gear 187, loosely mounted on a stud 188, fixed in the bracket 189, carried by the side frame 161 in the inking mechanism, as clearly shown in Fig. 5. The gear 187 is driven from the power-shaft 188 of the inking mechanism by a compound gear-train consisting of the pinion 190, journaled on the stud 191 and carrying a gear 192, which is driven from a pinion 193, fixed on the shaft 188. The stud 188 is preferably mounted concentrically with the shaft of the roller 63, or substantially so, in order that the throw of the pawl 178 will be the same for all positions of the auxiliary frame of the supplying part of the inking mechanism with reference to the other parts of the inking mechanism.

The ductor-roller 168 is mounted on a pair of arms 195, loosely pivoted on a rock-shaft 196, mounted in the frames 169 and 170 and provided with an arm 197, adapted to engage the cam 185. The arm 197 is held in contact with the cam 185 by an arm 198, provided at the other end of the shaft 196 and arranged to engage a spring 199, which is confined between said arm and an adjusting-nut 200 upon a rod 201, pivoted to a fixed part of the frame 169. To insure a uniform pressure between the ductor-roller and the fountain-roller on the one hand and between the ductor-roller and the distributing-roller 63 on the other hand, the arms 195 are connected with the shaft 196 by means of springs 202, carried by fixed collars 203 on the shaft 196 and arranged to loosely engage the arms 195. The tension of the springs 202 may be adjusted by means of fixed guides 204, adjustably mounted on the collars 203. The bearings for the ductor-roller 168 on the arms 195 are provided with hinged sections 205 to enable the roller to be readily removed.

Any suitable mechanism may be provided for fixing the fountain and ductor roller carrying frames with the fountain in level positions. As shown in Fig. 2, the fountains for

the two upper inking mechanisms are supported by brackets 206. The fountains of the two lower inking mechanisms on each side of the machine are supported from the brackets 206 by tie-rods 207 208.

So far as some of the features of my invention are concerned any suitable construction of damping mechanism may be adopted. In accordance with one feature of my invention, however, the several damping mechanisms or the water-applying parts thereof are constructed to be brought into or out of operative relation with the several design-cylinders, and this operation is effected by a movement about a common center. In accordance with another feature of the invention each of the several damping mechanisms includes a water-supplying and water distributing and applying parts, and the various rollers of the damping mechanism are yieldingly held in contact by means adapted to compensate effectively for variations in the diameters of the rollers, whereby frequent or accurate individual adjustment of the rollers is rendered unnecessary; also, to hold the rollers in operative position irrespective of the location of the damping mechanism in the press and irrespective of the gravity relation between adjacent rollers or between the applying-rollers and the design-surfaces. The damping mechanisms are also self-contained in that they are provided with independent driving means, from which all parts of the damping mechanisms not frictionally driven by the design-surfaces are operated, said driving means being associated with the damping mechanisms and forming a part thereof.

Referring now in detail to the particular embodiments of these features of my invention illustrated and more particularly to Figs. 3 and 19 to 37, inclusive, it will be observed that the several damping mechanisms are mounted on a pair of rings 212 and 213, mounted in concentric relation with the impression-cylinder on the inner surfaces of the side frames 5 and 6. The damping mechanisms for the two uppermost design-cylinders and the two lower design-cylinders at the left-hand side of the machine, as seen in Fig. 19, are mounted in pairs of frames 210 211, while the damping mechanisms for the two lower design-cylinders at the right-hand side of the machine, as illustrated in Fig. 19, are mounted in pairs of side frames 214 215, having a slightly-different shape from that of the frames 210 211. Each pair of side frames is secured together and braced by a rod 211'. The rings 212 and 213 are connected to move in unison by means of short gear-segments 216, which mesh with pinions 217 on the transverse shaft 218. The shaft 218 is controlled by a lever 219, (see Fig. 1,) which is yieldingly pressed in a direction to bring the damping mechanisms into contact with the design-surfaces by a compression-spring 220, confined on a rod 221.

221 between a shoulder thereon and a fixed 5 guide 222, the movement of the lever in the said direction being adjustably limited by nuts 223, threaded on the end of the rod 221. The lever 219 is positively operated in the opposite direction to separate the damping mechanisms from the design-cylinders by a pin 224, carried by the segment-disk 32. Each of the damping mechanisms shown includes a fountain- 10 tain 225, a fountain-roller 226, a ductor-roller 227, a distributing-roller 228, and a pair of applying-rollers 229. The ductor-roller 227 and the applying-rollers 229 are soft rollers made of any material suitable for use in connection with the damping solution employed and with the design-surfaces. They may, for example, be made of soft rubber covered with a fabric, the fabric preferably used being known to the trade as "moleskin." The fountain- 15 roller 226 is preferably made of brass covered with a suitable fabric, such as muslin, and is journaled in the side frames 210 211. In order that the damping mechanism may occupy various positions in the press and the fountain- 20 tain 225 be supported in a level position, the latter is adjustably mounted with relation to the other parts by any suitable means. As shown, the fountain is carried by a frame 230, adjustably mounted concentrically with the fountain-roller 226 and secured in the adjusted 25 position by means of bolts 231 passing loosely through slots 232 and entering certain of the threaded holes 233 in the frames 210 211.

30 35 Any suitable means may be provided for driving the fountain-roller. In accordance with the embodiment of the invention illustrated the fountain-roller is driven by disk 235, the sleeve of which is splined to the shaft 236 of the fountain-roller and is journaled in bushings 237 238, the latter of which is threaded in the frame-piece 211, so that it may be adjusted therein to vary the position of the disk and hold the same up to its work. The bush- 40 45 ing 237 serves as a support for the frame 230 of the fountain. The friction-disk 235 is driven by a wheel 240, splined on a shaft 241, which is journaled in brackets 242 and 243 and arranged transversely on the disk 235, as shown. The wheel 240 may be adjusted to engage the disk 235 at various distances from its center by means of the guide-bracket 244, which may be secured at various positions along the slot-bar 245 by a clamp-nut 246. 50 55 The shaft 241 may be driven in any suitable way. As shown it is driven by a worm-wheel 247; secured at one end thereof and engaging a worm 248, formed on one end of the drive-shaft 250 of the damping mechanism. Back- 60 65 ward rotation of the fountain-roller by the momentum of the ductor-roller 222 is prevented by a roller-detent 251, mounted in a recess in the bushing 238 in position to engage the sleeve of the disk 235 and held constantly in operative position by a spring 252. (See

Figs. 36 and 37.) The ductor-roller 227 is mounted in a pair of arms 255, pivoted on a rock-shaft 256, journaled in the frame 210 211, the arms 255 being yieldingly confined to rock with the shaft 256 by means of spring 257, 70 carried by the fixed collars 258, as and for the reasons previously described in connection with the ink ductor-roller. The shaft 256 is provided at one end with an arm 260, to which is pivoted a forked bar 261, carrying a friction-roller 262, adapted to engage a cam 263, fixed on the outer end of the shaft 241. The opposite end of shaft 256 is provided with an arm 264, between which and an adjustable collar on a pivoted rod 266 is confined a compression-spring 265.

In accordance with one feature of the invention the damping mechanism is constructed to be driven by the design-cylinder when in contact therewith, and means are provided whereby the damping mechanism is driven when not in contact with the design-cylinder at substantially the surface speed of the design-cylinder. The mechanism whereby this feature of the invention may be carried into effect may be widely varied in detail. As shown, a distributing-roller 228 is driven from the shaft 250 when the damping mechanism is not in operative position by a belt 268, passing around a pulley 269 on the shaft 95 250, and a pulley 270, mounted on a sleeve 271, keyed to the shaft of the roller 228. The pulley 270 is connected to the sleeve 271 through a friction-clutch roller 272, which is held in operative position by a spring 273. (See Figs. 25 and 26.) This driving mechanism for the roller 228 drives the same and the applying-rollers 229 at a slightly-slower speed than that of the design-cylinder when the applying-rollers are not in contact with the design-cylinder, but allows the rollers to be driven by the design-cylinder at a faster speed when in contact therewith.

In accordance with one feature of the invention the applying-rollers 229 are yieldingly held in contact with the design-cylinder and with the distributing-roller 228 when in operative position by means adapted to compensate effectively for variations in the diameters of the applying-rollers and adapted to hold the rollers in operative position irrespective of the gravity relation between the applying-rollers and the design-cylinder. Any suitable means may be provided for this purpose. In accordance with the construction shown the rollers 229 are supported by auxiliary frames 275, pivotally mounted concentrically with roller 228 and bushings 276, which form also the bearings for the shaft of said roller. These frames 275 are secured in their adjusted positions by the bolts 277 passing through slots in the frames and into the frames 210 211. The applying-rollers 229 are independently mounted in oppositely-arranged supports 278, pivoted at 279 to the 130

frames 275, as shown. The rollers 229 are journaled in boxes 280, slidably mounted in slots in the supports 278, and are pressed inwardly by the compression-springs 281. One of the supports 278 is provided with a stop-finger 282, which acts to limit the movement of the rollers away from the roller 228 and toward the design-cylinder. The stop 282 comes into operation before the boxes 280 reach the inner ends of the slots in the supports 278, thus causing the rollers 229 to be yieldingly held in contact with the distributing-roller 228 when the damping mechanism is out of contact with the design-cylinder. When the damping mechanism is brought into contact with the design-cylinder, the rollers 229 are forced back with relation to the distributing-roller 228, the stop-finger 282 being thus separated from the opposite arm 278 and the rollers slightly separated, so that they will be yieldingly held in contact both with the roller 228 and with the design-cylinder by the springs 281.

The shafts 250, which independently drive all parts of the damping mechanisms not frictionally driven from the design-cylinders when the damping mechanisms are in operative position, receive motion from the gear 54, carried by the impression-drum, said gear 54 thus constituting a common actuating part for the independent driving-shafts of the damping mechanisms.

The damping mechanisms for the two lower design-cylinders (shown to the right in Fig. 19) are each provided with an extra distributing-roller 226', the purpose of which is to enable the ductor 227 to receive water from the fountain-roller 226 without interfering with the leveling adjustment of the fountain 225. This necessitates a little variation in the shape of the frames of the various damping mechanisms, which are in other respects alike.

The operation of the machine as a whole will be clear from the above description, in which the operation of the various parts has been set forth in connection with the description of the construction thereof. It only remains to set forth the operation of the controlling means for the printing, inking, and damping mechanisms when these mechanisms are brought into and out of their operative relations. In Fig. 1 the parts are shown in their inoperative positions. Assuming that the machine is equipped with design-surfaces, that the inking and damping mechanisms are supplied with ink and water, respectively, and that the press has been set in motion, the printing operation is started by moving the segment-disks 31 and 32 in the direction indicated by the arrow in Fig. 1. This causes the design-cylinders and the inking and damping mechanisms to move toward their operative positions, the connections between all said parts and the disks 31, 32 being in operative engagement with said disks, as illustrated

in Fig. 1. The parts are so constructed and timed, however, that the damping mechanisms will be brought into contact with the design-cylinders before the inking mechanisms are brought into such contact and before the design-cylinders are brought into contact with the impression-cylinder or the paper thereon. The inking mechanisms are next brought into contact with the design-cylinders, and finally the latter are brought into contact with the paper, whereupon the printing operation will proceed until the controlling mechanism is moved in the opposite direction. This predetermined sequence in which the parts are brought into operation is brought about by so shaping the cam-slots in the rings 30 that the design-cylinders move slowly or not at all during the first part of the movement of the controlling mechanisms or until the damping and inking rollers are in contact therewith.

The damping mechanisms are brought into contact with the design-cylinders in the first part of the movement of the segment, the roller 224 moving away from the lever 229 when this operation is completed. The further movement of the controlling mechanism brings the ink-applying rollers into contact with the design-cylinders, and then the ink-applying rollers and design-cylinders move together until the design-cylinders are brought into contact with the impression-cylinder, whereupon the movement of the controlling mechanism is stopped. Any slight inequalities in the movements of the design-cylinders and the frames carrying the ink-applying rollers after the latter are brought into contact with the design-cylinders are equalized by the yielding supports for the applying-rollers. Preferably the movements of the parts are so timed that the ink-applying rollers will be yieldingly held in contact with the design-cylinders before the latter reach the printing position, a thorough application of the ink, and consequently good impressions from the very beginning of the printing operation, being thus secured.

To stop the printing operation, the sequence in which the parts are separated should be the reverse of that in which they are brought into operation, and that reverse sequence is secured by merely reversing the movement of the controlling means. The design-cylinders are first separated from the impression-cylinder, then the inking mechanisms are separated from the design-cylinders, and, lastly, the damping mechanisms are separated from the design-cylinders. While it is desirable to preserve the above sequence to avoid injury to the parts and especially to the design-carrying surfaces, the intervals between the times when the various parts are brought into or out of operation may be very short or sensibly instantaneous. It is not necessary, moreover, to move the controlling mechanism, and

with it the inking and damping mechanisms, through their full range to stop and start the printing operation. It will be observed that the printing operation will be stopped by 5 merely moving the controlling mechanism far enough to separate the design-cylinders from the impression-cylinder. It is preferred, however, to move the controlling mechanism far enough to separate all the parts, so that there 10 may be nothing in contact with the design-surfaces when the machine is stopped, thus leaving said surfaces free to receive a coating of gum or a similar protecting layer.

It will be noted that the connections between 15 the design-cylinders and the connecting mechanisms and the common actuating means are positive connections, while the connection between the damping mechanisms and the common actuating means is not positive and 20 does not connect said parts at all times. It is to be observed, however, that the form of any of these connections is immaterial, and so far as some of the features of my invention are concerned they may be such that the various 25 parts of the press may be moved into or out of operative position independently of each other.

Among the advantages of my invention not 30 previously referred to the following may be mentioned: All the parts are readily accessible, each mechanism being independent of the others. The parts of the machine may be readily assembled and any particular part may be removed and replaced without disturbing 35 other parts of the press. The inking mechanisms are free from all obstructions and are in full view of the operator and are easily accessible for cleaning and by reason of the fact that they are fixed and extend outwardly 40 away from the main center of the machine the distributing surfaces or areas may be made as large as desired and without an undue multiplication and complication of parts. The ink-fountains are open and of simple construction 45 and they can be readily inspected and kept supplied with ink. The flow of ink through the distributing mechanism is divided into a plurality of independent streams which are independently distributed and independently 50 applied to the printing-surfaces. The damping mechanisms are simple in construction, compact, and have open fountains and ample means for regulating the supply of damping fluid. Many other advantages of the 55 invention and the various features thereof will readily appear to those skilled in the art.

The invention in its broader aspects is not limited to the particular mechanism illustrated and described nor to any particular mechanism 60 by which it has been or may be carried into effect, as numerous changes may be made in the construction, many of which will readily suggest themselves to skilled press-builders.

My invention, therefore, is to be regarded as 65 including all forms of mechanism which may

serve to carry the improvements and combinations herein disclosed into practical effect.

Having thus described my invention, what I claim as novel, and desire to secure by Letters Patent, is—

1. A rotary printing-press including in combination, a plurality of design-cylinders, a plurality of inking mechanisms therefor, each comprising a distributing part and an applying part, and means whereby two or more of 75 said applying parts and the corresponding design-cylinders may at will be brought into or out of coöperative relation without disturbing the corresponding distributing parts.

2. A rotary printing-press including in combination, a plurality of design-cylinders, a plurality of inking mechanisms therefor, each comprising a distributing part and an applying part, and means including a member common to the applying parts of two or more of 80 said inking mechanisms whereby said two or more applying parts and the corresponding design-cylinders may at will be brought into or out of coöperative relation without disturbing the corresponding distributing parts.

3. A rotary printing-press including in combination, a plurality of design-cylinders, a plurality of inking mechanisms therefor, each comprising a distributing part, an applying part, and a conveying part between the distributing and applying parts, and means 95 whereby two or more of said applying parts and the corresponding design-cylinders may at will be brought into or out of coöperative relation without disturbing the corresponding distributing parts.

4. A rotary printing-press including in combination, a curved circumferentially-continuous design member, an inking mechanism therefor comprising a distributing part, an 105 applying part for continuously applying ink to the design member while the press is printing, and means whereby said applying part and the design member may at will be readily separated or brought together without moving the distributing part.

5. A rotary printing-press including in combination, a curved circumferentially-continuous design member, an inking mechanism therefor comprising a distributing part, an 115 applying part for continuously applying ink to the design member while the press is printing, a conveying part between the distributing and applying parts, and means whereby said applying part and the design member may 120 at will be readily separated or brought together without moving the distributing part.

6. A rotary printing-press including in combination, a plurality of curved circumferentially-continuous design members, a plurality 125 of inking mechanisms therefor, each comprising a distributing part, an applying part for continuously applying ink to the design member while the press is printing, and means whereby two or more of said applying parts 130

and their corresponding design members may at will be readily brought into or out of coöperative relation without moving the distributing part.

5 7. A rotary printing-press including in combination, an impression-cylinder, a design-cylinder, an inking mechanism including a distributing part and an applying part, means for separating the design and impression cylinders, and means for separating the design-cylinder and the applying part of the inking mechanism without moving the distributing part thereof.

15 8. A rotary printing-press including in combination, an impression mechanism, a plurality of design-cylinders, an inking mechanism for each design-cylinder including a distributing part and an applying part, means for separating two or more of the design-cylinders and the impression mechanism, and means for separating two or more of the design-cylinders and the applying parts of the corresponding inking mechanisms without moving the distributing parts thereof.

25 9. A rotary printing-press including in combination, an impression mechanism, a plurality of design-cylinders, inking mechanism for each design-cylinder including a distributing part and an applying part, means including a member common to two or more of the design-cylinders for separating said two or more cylinders and the impression mechanism, and means including a member common to the applying parts of two or more of the inking mechanisms for separating said two or more applying parts and the corresponding cylinders without moving the distributing parts of said two or more inking mechanisms.

40 10. A rotary printing-press including in combination, an impression-cylinder, a plurality of design-cylinders arranged in coöperative relation therewith, an inking mechanism for each design-cylinder including a distributing part and an applying part, means for separating the design and impression cylinders, and means for separating the design-cylinders and the applying parts of the corresponding inking mechanisms without moving the distributing parts thereof.

45 11. A rotary printing-press including in combination, an impression-cylinder, a plurality of design-cylinders arranged in coöperative relation therewith, an inking mechanism for each design-cylinder including a distributing part and an applying part, means including a member common to two or more of said design-cylinders for separating said two or more cylinders and the impression-cylinder, and means including a member common to the applying parts of two or more of said inking mechanisms for separating the applying parts of said two or more inking mechanisms and the corresponding design-cylinders without moving the distributing parts of said

65 two or more inking mechanisms.

12. An inking mechanism for a printing-press including a plurality of hard and soft rollers arranged alternately in series, and means for yieldingly holding a plurality of soft rollers in contact with the adjacent hard rollers, said means acting on the soft rollers individually and being adapted to compensate for variations in the diameters of the rollers whereby frequent or accurate individual adjustment of the rollers is rendered unnecessary. 70

13. A rotary printing-press including in combination, a design-cylinder, an inking mechanism including a plurality of distributing-rollers, means for yieldingly holding adjacent rollers in contact, a plurality of applying-rollers, and means for yieldingly holding said applying-rollers in position to apply ink to the design, said holding means acting on the several rollers individually and being 80 adapted to compensate for variations in the diameters of the rollers whereby frequent or accurate individual adjustment of the rollers is rendered unnecessary. 85

14. A rotary printing-press including in combination, a design-cylinder, an inking mechanism including a distributing part comprising a plurality of rollers, means for yieldingly holding adjacent rollers in contact, an applying part comprising a plurality of applying-rollers and means for yieldingly holding said rollers in position for applying ink to the design, a conveying part, and means for yieldingly holding said conveying part in operative relation with both the distributing and applying parts, said holding means acting on the several rollers individually and being adapted to compensate for variations in the diameters of the rollers whereby frequent or accurate individual adjustment of the rollers is rendered unnecessary. 90 95

15. A rotary printing-press including in combination, a plurality of design-cylinders, an inking mechanism for each cylinder including a plurality of hard and soft rollers, and means for yieldingly holding adjacent rollers in contact, said means being adapted to compensate for variations in the diameters of the rollers whereby frequent or accurate individual adjustment of the rollers is rendered unnecessary. 100 110

16. A rotary printing-press including in combination, a plurality of design-cylinders, an inking mechanism for each cylinder including a plurality of hard and soft distributing-rollers, means for yieldingly holding adjacent rollers in contact, a plurality of applying-rollers, and means for yieldingly holding said rollers in position to apply ink to the design, said means for yieldingly holding the several rollers being adapted to compensate for variations in the diameters of the rollers whereby frequent or accurate individual adjustment of the rollers is rendered unnecessary. 115 120 125

17. A rotary printing-press including in

combination, a design-cylinder, an inking mechanism therefor including an applying-roller, means for moving said roller into and out of position for applying ink to the design, and means for yieldingly holding said roller in operative position, said means being adapted to compensate for variations in the diameter of the roller whereby frequent or accurate adjustment of the roller is rendered unnecessary.

18. A rotary printing-press including in combination, a design-cylinder, an inking mechanism therefor including a plurality of applying-rollers, one or more intermediate rollers, means for moving said applying-rollers into or out of position for applying ink to the design, means for yieldingly holding said intermediate roller or rollers in contact with said applying-rollers, and means for yieldingly holding said applying-rollers in operative position, said means for yieldingly holding the several rollers being adapted to compensate for variations in the diameters of the rollers whereby frequent or accurate individual adjustment of the rollers is rendered unnecessary.

19. A rotary printing-press including in combination, a design-cylinder, an inking mechanism therefor including a distributing part, an applying part, means for moving the applying part into or out of position for applying ink to the form, a conveying part, and means for yieldingly holding the conveying part in contact with both the distributing and applying parts irrespective of the position of the latter part.

20. A rotary printing-press including in combination, an impression-cylinder, a design-cylinder, means for moving the design-cylinder into or out of operative relation with the impression-cylinder, an inking mechanism including an applying-roller, a support for the applying-roller and means for yieldingly holding said applying-roller in operative position, said means being arranged between the roller and its support and being adapted to compensate for variations in the diameter of the roller.

21. A rotary printing-press including in combination, an impression-cylinder, a design-cylinder, means for moving the design-cylinder into or out of operative relation with the impression-cylinder, an inking mechanism including an applying-roller, means for moving the applying-roller into or out of operative position, and means for yieldingly holding said applying-roller in operative position, said holding means being adapted to compensate for variations in the diameter of the roller.

22. A rotary printing-press including in combination, an impression-cylinder, a design-cylinder, means for moving the design-cylinder into or out of operative relation with the impression-cylinder, an inking mechanism

including a distributing part, an applying part, means for yieldingly holding the applying part in operative position, a conveying part, and means for yieldingly holding the conveying part in contact with both the distributing and applying parts.

23. A rotary printing-press including in combination, an impression-cylinder, a design-cylinder, means for moving the design-cylinder into or out of operative relation with the impression-cylinder, an inking mechanism including a distributing part, an applying part, means for moving the applying part into or out of operative position, means for yieldingly holding the applying part in operative position, a conveying part, and means for yieldingly holding the conveying part in operative relation with both the distributing and applying parts irrespective of the position of the latter part.

24. A rotary printing-press including in combination, an impression mechanism, a plurality of design-cylinders, means for separating and bringing together said impression mechanism and said design-cylinders, an inking mechanism for each design-cylinder including an applying-roller, and means for yieldingly holding said applying-roller in operative position, said means being arranged between the roller and its support and being adapted to compensate for variations in the diameter of the roller.

25. A rotary printing-press including in combination, an impression mechanism, a plurality of design-cylinders, means for moving the design-cylinders into or out of operative relation with the impression mechanism, an inking mechanism for each design-cylinder including a distributing part, an applying part, means for moving said applying part into or out of operative position, and means for yieldingly holding said applying part in operative position, a conveying part, and means for yieldingly holding said conveying part in operative relation with both the distributing and applying parts.

26. A rotary printing-press including in combination, an impression mechanism, a plurality of design-cylinders, means for moving the design-cylinders into or out of operative relation with the impression mechanism, an inking mechanism for each design-cylinder including an applying-roller, means for moving the applying-roller into or out of operative position, and means for yieldingly holding said applying-roller in operative position, said means being adapted to compensate for variations in the diameter of the roller.

27. A rotary printing-press including in combination, a design-cylinder, an inking mechanism therefor including a plurality of distributing-rollers, means for yieldingly holding said rollers in contact, a plurality of applying-rollers, means for moving the applying-rollers into or out of operative posi-

tion, and means for yieldingly holding the applying-rollers in operative position, said holding means being adapted to compensate for variations in the diameters of the rollers 5 whereby frequent or accurate individual adjustment of the rollers is rendered unnecessary.

28. A rotary printing - press including in combination, an impression-cylinder, a design-cylinder, means for separating the design and impression cylinders and for bringing them together, an inking mechanism including a plurality of distributing-rollers, means for yieldingly holding the adjacent rollers in contact, 10 a plurality of applying-rollers, means for moving the applying-rollers into or out of operative position, means for yieldingly holding the applying-rollers in operative position, said holding means being adapted to 15 compensate for variations in the diameters of the rollers whereby frequent or accurate individual adjustment of the rollers is rendered unnecessary.

29. An inking mechanism for a printing-press including in combination, a plurality of rollers, and means for yieldingly holding certain of said rollers in operative position, said inking mechanism being adapted to occupy various positions in the press as regards the 25 action of gravity on its various rollers, and said means being adapted to compensate for variations in the diameters of the rollers and to yieldingly hold the rollers in operative position irrespective of their gravity relations 30 with respect to the coöperating parts.

30. A rotary printing - press including in combination, a plurality of design-cylinders, a plurality of inking mechanisms therefor, each comprising a plurality of rollers, and 40 means for yieldingly holding certain of said rollers in operative position the movement of the rollers toward their operative positions being limited by the contact of the rollers with the coöperating parts, said inking mechanisms being located in various positions with 45 respect to the action of gravity on the rollers thereof, and said holding means being adapted to hold the rollers in operative position irrespective of their gravity relations to the 50 coöperating parts.

31. A rotary printing - press including in combination, a plurality of design-cylinders, a plurality of inking mechanisms therefor, each comprising a plurality of rollers, and 55 means for yieldingly holding certain of said rollers in operative position, said inking mechanisms being located in various positions with respect to the action of gravity on the rollers thereof, and said holding means being adapted to compensate for variations in the diameters of the rollers and to hold them in their operative positions irrespective of their gravity relations to the coöperating parts.

32. A rotary printing - press including in combination, a plurality of design-cylinders,

a plurality of inking mechanisms therefor, each including an applying-roller and means for yieldingly holding said applying-roller in operative position the movement of the rollers toward their operative positions being limited by the contact of the rollers with the coöperating parts, said inking mechanisms being located in various positions with respect to the action of gravity on the applying-rollers thereof, and said holding means being adapted to 75 hold the applying-rollers in operative position irrespective of their gravity relations to the corresponding design-cylinders.

33. A rotary printing - press including in combination, a plurality of design-cylinders, 80 a plurality of inking mechanisms therefor, each including an applying-roller and means for yieldingly holding said applying-roller in operative position, said inking mechanisms being located in various positions with respect to the action of gravity on the applying-rollers thereof, and said holding means being adapted to 85 compensate for variations in the diameters of the rollers and to hold them in operative position irrespective of their gravity relations to the corresponding design-cylinders. 90

34. A rotary printing-press cylinder including in combination, a plurality of design-cylinders, a plurality of inking mechanisms therefor, each including an applying-roller, means 95 for moving said applying-roller into or out of operative relation with the corresponding design - cylinder, and means for yieldingly holding said roller in operative position the movement of the applying-roller toward its operative position being limited by the contact of the roller with the design-surface, said applying-rollers being located in various gravity relations with respect to the corresponding design-cylinders and said holding means being 100 adapted to hold the applying-rollers in operative position irrespective of their gravity relations to the design-cylinders. 105

35. A rotary printing-press cylinder including in combination, a plurality of design-cylinders, a plurality of inking mechanisms therefor, each including an applying-roller, means for moving said applying-roller into or out of operative relation with the corresponding design - cylinder, and means for yieldingly 110 holding said roller in operative position, said applying-rollers being located in various gravity relations with respect to the corresponding design-cylinders and said holding means being adapted to compensate for variations 115 in the diameters of the applying-rollers and to hold them in operative position irrespective of their gravity relations to the corresponding design-cylinders. 120

36. A rotary printing - press including in 125 combination, a plurality of design-cylinders, a plurality of inking mechanisms therefor, each including a plurality of ink-distributing rollers, means for yieldingly holding adjacent distributing-rollers in contact, an applying- 130

roller, means for yieldingly holding the applying-roller in operative position with relation to the design-cylinder the movement of said roller toward its operative position being limited by the contact of the roller with the design-surface, said inking mechanisms being located in various positions with respect to the action of gravity on the various rollers thereof and said holding means being adapted to hold the several rollers in operative position irrespective of their gravity relations to the coöperating parts.

37. A rotary printing-press including in combination, a plurality of design-cylinders, a plurality of inking mechanisms therefor, each including a plurality of ink-distributing rollers, means for yieldingly holding adjacent distributing-rollers in contact, an applying-roller, means for yieldingly holding the applying-roller in operative position with relation to the design-cylinder, said inking mechanisms being located in various positions with respect to the action of gravity on the various rollers thereof and said holding means being adapted to compensate for variations in the diameters of the several rollers and to hold them in operative position irrespective of their gravity relations to the coöperating parts.

38. A rotary printing-press including in combination, a plurality of design-cylinders, a plurality of inking mechanisms therefor, each including a plurality of ink-distributing rollers, means for yieldingly holding adjacent distributing-rollers in contact, an ink-applying roller, means for moving the ink-applying roller into or out of operative relation with the corresponding design-cylinder the movement of said roller toward its operative position being limited by the contact of the roller with the design-surface, and means for yieldingly holding the applying-roller in operative position, said inking mechanisms being located in various positions with respect to the action of gravity on the rollers thereof and said holding means being adapted to hold the several rollers in their operative positions irrespective of their gravity relations to the coöperating parts.

39. A rotary printing-press including in combination, a plurality of design-cylinders, a plurality of inking mechanisms therefor, each including a plurality of ink-distributing rollers, means for yieldingly holding adjacent distributing-rollers in contact, an ink-applying roller, means for moving the ink-applying roller into or out of operative relation with the corresponding design-cylinder, and means for yieldingly holding the applying-roller in operative position, said inking mechanisms being located in various positions with respect to the action of gravity on the rollers thereof and said holding means being adapted to compensate for variations in the diameters of the several rollers and to hold them in their

operative positions irrespective of their gravity relations to the coöperating parts.

40. A rotary printing-press including in combination, an impression-cylinder, a plurality of design-cylinders, means for moving the design-cylinders into or out of operative relation with the impression-cylinder, an inking mechanism for each design-cylinder including a plurality of distributing-rollers, means for yieldingly holding the adjacent rollers in contact the movement of said rollers toward their operative positions being limited by the contact of the rollers with the coöperating parts, a plurality of applying-rollers and means for yieldingly holding the applying-rollers in operative position, said inking mechanisms being located in various positions in the press with respect to the action of gravity on their various rollers, and said holding means being adapted to hold the several rollers in operative position irrespective of their gravity relation to the coöperating parts.

41. An inking mechanism for a rotary printing-press, including in combination an ink-distributing mechanism, an ink-fountain and a ductor-roller, said ink-fountain, and said ductor-roller being adjustable with respect to the distributing mechanism whereby the fountain may be set in a level position for various positions of the inking mechanism in the press.

42. An inking mechanism for a printing-press including in combination, an ink-fountain, a fountain-roller, a ductor-roller, and operating devices for the fountain-roller, all of which parts are mounted on a common center and are adjustable thereon for various positions of the inking mechanism in the press.

43. An inking mechanism for a printing-press including in combination, an ink-fountain, a fountain-roller, a ductor-roller, and operating devices for the ductor-roller, all of which parts are mounted on a common center and are adjustable thereon for various positions of the inking mechanism in the press.

44. An inking mechanism for a printing-press including in combination, an ink-fountain, a fountain-roller, a ductor-roller, and operating devices for both the fountain and ductor rollers, all of which parts are mounted on a common center and are adjustable thereon for various positions of the inking mechanism in the press.

45. An inking mechanism for a printing-press including in combination, an ink-fountain, a fountain-roller, a ductor-roller, pawl-and-ratchet devices for rotating the fountain-roller, and cam-actuated devices for operating the ductor-roller, all of which parts are mounted on a common center and are adjustable thereon for various positions of the inking mechanism in the press.

46. A rotary printing-press including in combination, a plurality of design-cylinders,

a plurality of interchangeable inking mechanisms, each including an ink-fountain and a ductor, both adjustable with relation to the other parts of the inking mechanism whereby the fountain may be set in a level position for various locations of the inking mechanism in the press.

47. In an inking mechanism for a printing-press, the combination of an ink-distributing mechanism including a plurality of rollers, a fountain, and a ductor, said fountain and ductor being pivotally mounted concentrically with one of the rollers of the distributing mechanism and adjustable with relation to the distributing mechanism whereby the inking mechanism may be placed in various positions in the press.

48. An ink-distributing mechanism for a printing-press including a plurality of series of distributing-rollers, said series including a plurality of sets of rollers the rollers of each set being connected together, and means consisting of a shaft and oppositely-arranged cranks for vibrating adjacent sets of rollers in opposite directions.

49. A rotary planographic printing-press including in combination, a curved circumferentially-continuous planographic design member, a damping mechanism therefor, an inking mechanism therefor comprising a distributing part, and applying part for continuously applying ink to the design member while the press is printing, and means whereby said applying part and said design member may at will be readily separated and brought together without moving the distributing part.

50. A rotary multicolor planographic printing-press including in combination, a plurality of curved circumferentially-continuous planographic design members, a plurality of damping mechanisms therefor, a plurality of inking mechanisms therefor each comprising a distributing part, an applying part for continuously applying ink to the corresponding design member while the press is printing, and means whereby two or more of said applying parts and their corresponding design members may at will be readily brought into or out of coöperative relation without moving the distributing parts.

51. A rotary planographic printing-press including in combination, an impression-cylinder, a planographic design-cylinder, a damping mechanism, an inking mechanism including a distributing part and an applying part, means whereby the impression and design cylinders may at will be readily separated and brought together, and means whereby the design-cylinder and the applying part of the inking mechanism may at will be readily separated and brought together without moving the distributing part of the inking mechanism.

52. A rotary multicolor planographic printing-press including in combination, an impres-

sion mechanism, a plurality of planographic design-cylinders, a damping mechanism for each design-cylinder, an inking mechanism for each design-cylinder including a distributing part and an applying part, means whereby the design-cylinders and the impression mechanism may at will be readily separated and brought together, and means whereby the design-cylinders and the applying parts of the inking mechanism may at will be readily separated and brought together without moving the distributing parts of the inking mechanism.

53. A rotary multicolor planographic printing-press including in combination, a plurality of design-cylinders, a plurality of damping mechanisms therefor, a plurality of inking mechanisms therefor, each comprising a distributing part and an applying part, and means whereby said applying parts may at will be readily moved into and out of coöperative relation with the corresponding design-cylinders without moving the corresponding distributing parts.

54. A rotary planographic printing-press including in combination, an impression-cylinder, a planographic design-cylinder, a damping mechanism therefor, an inking mechanism therefor including a distributing part and an applying part, means whereby the design-cylinder may at will be readily moved into and out of coöperative relation with the impression-cylinder, and means whereby the applying part of the inking mechanism may at will be readily moved into and out of operative relation with the design-cylinder without moving the distributing part of the inking mechanism.

55. A rotary multicolor planographic printing-press including in combination, an impression mechanism, a plurality of planographic design-cylinders, a damping mechanism for each design-cylinder, an inking mechanism for each design-cylinder including a distributing part and an applying part, means whereby the design-cylinders may at will be readily moved into and out of coöperative relation with the impression mechanism, and means whereby the applying parts of the inking mechanisms may at will be readily moved into and out of operative relation with the design-cylinders without moving the distributing parts of the inking mechanisms.

56. A rotary multicolor planographic printing-press including in combination, an impression mechanism, a plurality of planographic design-cylinders, a damping mechanism for each design-cylinder, an inking mechanism for each design-cylinder including a distributing part and an applying part, means common to two or more of said design-cylinders for moving the same into or out of coöperative relation with the impression mechanism, and means including a member common to two or more of the inking mechanisms for moving the apply-

ing parts of said two or more inking mechanisms into or out of operative relation with the corresponding design-cylinders without moving the distributing parts of the inking mechanisms.

57. A rotary multicolor planographic printing-press including in combination, an impression mechanism, a plurality of planographic design-cylinders, a damping mechanism for each design-cylinder, an inking mechanism for each design-cylinder including a distributing part and an applying part, means whereby the design-cylinders and the impression mechanism may at will be readily separated and brought together, means whereby the design-cylinders and the damping mechanisms may at will be readily separated and brought together, and means whereby the design-cylinders and the applying parts of the inking mechanism may at will be readily separated and brought together without moving the distributing parts of the inking mechanisms.

58. A rotary multicolor planographic printing-press including in combination, an impression mechanism, a plurality of planographic design-cylinders, a damping mechanism for each design-cylinder, an inking mechanism for each design-cylinder including a distributing part and an applying part, means whereby the design-cylinders may at will be readily moved into and out of operative relation with the impression mechanism, means whereby the damping mechanisms may at will be readily moved into and out of operative relation with the design-cylinders, and means whereby the applying parts of the inking mechanisms may at will be readily moved into and out of operative relation with the design-cylinders without moving the distributing parts of the inking mechanisms.

59. A rotary multicolor planographic printing-press including in combination, an impression-cylinder, a plurality of planographic design-cylinders, a plurality of damping mechanisms, a plurality of inking mechanisms each including a distributing part and an applying part, means including a part common to two or more of the design-cylinders for moving said cylinders into or out of operative relation with the impression-cylinder, means including a part common to two or more of said damping mechanisms for moving them into or out of operative relation with the design-cylinders, and means common to two or more of the inking mechanisms for moving the applying parts thereof into or out of operative relation with the corresponding design-cylinders without moving the distributing parts of the inking mechanisms.

60. A rotary multicolor planographic printing-press including in combination, a plurality of planographic design-cylinders, a plurality of damping mechanisms therefor, a plurality of inking mechanisms therefor each comprising a plurality of rollers and means for yield-

ingly holding adjacent rollers in contact, said means being adapted to compensate for variations in the diameters of the rollers whereby frequent or accurate individual adjustment of the rollers is rendered unnecessary.

70 61. A rotary multicolor planographic printing-press including in combination, an impression-cylinder, a plurality of planographic design-cylinders, a damping mechanism for each design-cylinder, an inking mechanism for each design-cylinder comprising a plurality of rollers and means for yieldingly holding adjacent rollers in contact, said means being adapted to compensate for variations in the diameters of the rollers whereby frequent or accurate individual adjustment of the rollers is rendered unnecessary.

75 62. A rotary multicolor planographic printing-press including in combination, an impression-cylinder, a planographic design-cylinder, means for moving the design-cylinder into or out of operative relation with the impression-cylinder, a damping mechanism, and an inking mechanism including an applying-roller and means for yieldingly holding said applying-roller in operative position, said means being adapted to compensate for variations in the diameter of the roller.

80 63. A rotary planographic printing-press including in combination, an impression mechanism, a plurality of planographic design-cylinders, means whereby the design-cylinders and the impression mechanism may at will be readily separated and brought together, a damping mechanism for each design-cylinder, 85 and an inking mechanism for each design-cylinder including an applying-roller and means for yieldingly holding said roller in operative position, said means being adapted to compensate for variations in the diameter of the roller.

90 64. A rotary multicolor planographic printing-press including in combination, an impression-cylinder, a plurality of planographic design-cylinders, means for readily moving the design-cylinders at will into or out of operative relation with the impression-cylinder, a damping mechanism for each design-cylinder, an inking mechanism for each design-cylinder including an applying-roller, means for 95 readily moving the applying-rollers at will into and out of operative position, and means for yieldingly holding the applying-rollers in their operative positions, said means being adapted to compensate for variations in the 100 diameters of the rollers.

105 65. A rotary multicolor planographic printing-press including in combination, an impression-cylinder, a plurality of planographic design-cylinders, means for readily moving the design-cylinders at will into or out of operative relation with the impression-cylinder, a damping mechanism for each design-cylinder including one or more applying-rollers, means for readily moving said applying-rollers at 110

- will into or out of operative position, means for yieldingly holding said applying-rollers in their operative positions, an inking mechanism for each design-cylinder including one or 5 more applying-rollers, means for readily moving said ink-applying rollers at will into or out of their operative positions, means for yieldingly holding said ink-applying rollers in their operative positions, said holding 10 means for the several applying-rollers being adapted to compensate for variations in the diameters of the rollers whereby frequent or accurate individual adjustment of the rollers is rendered unnecessary.
- 15 66. A rotary multicolor planographic printing-press including in combination, an impression-cylinder, a plurality of planographic design-cylinders, means including a part common to two or more of said design-cylinders 20 to move them into or out of operative relation with the impression-cylinder, a damping mechanism for each design-cylinder, means including a part common to two or more of said damping mechanisms for moving them 25 into or out of operative relation with the corresponding design-cylinders, an inking mechanism for each printing-cylinder including one or more applying-rollers, means including a part common to two or more of said 30 inking mechanisms for moving the applying-rollers therefor into or out of operative position, and means for yieldingly holding the applying-rollers of said two or more inking mechanisms in their operative positions, the 35 means for yieldingly holding the applying-rollers being adapted to compensate for variations in the diameters of the rollers whereby frequent or accurate individual adjustment of the rollers is rendered unnecessary.
- 40 67. A rotary planographic printing-press including in combination, a planographic design-cylinder, a damping mechanism, an inking mechanism including a plurality of distributing-rollers, means for yieldingly holding 45 adjacent rollers in contact, a plurality of applying-rollers, means for yieldingly holding said applying-rollers in position to apply ink to the design, said holding means including springs so mounted and arranged as to 50 compensate for variations in the diameters of the rollers, and means for varying the force of the springs.
68. A rotary planographic printing-press including in combination, a plurality of planographic design-cylinders, a damping mechanism, an inking mechanism for each cylinder including a plurality of rollers, means for yieldingly holding adjacent rollers in contact, said means including springs constructed 55 and arranged to compensate for variations in the diameters of the rollers, and means for varying the force of the springs.
69. A rotary planographic press including in combination a plurality of planographic design-cylinders, a damping mechanism for each 65
- cylinder, an inking mechanism for each cylinder including a plurality of hard and soft rollers arranged alternately in series, means for yieldingly holding the soft rollers in contact with the adjacent hard rollers, said means including springs constructed and arranged to compensate for variations in the diameters of the rollers, and means for varying the force of the springs. 70
70. A rotary planographic printing-press including in combination, a plurality of planographic design-cylinders, a damping mechanism for each cylinder, an inking mechanism for each cylinder including a plurality of distributing-rollers, means for yieldingly holding adjacent rollers in contact, a plurality of applying-rollers, means for yieldingly holding said rollers in position to apply ink to the design, said holding means including springs constructed and arranged to compensate for variations in the diameters of the rollers, and means whereby the force of the springs may be varied. 80
71. A rotary planographic printing-press including in combination, a plurality of planographic design-cylinders, a damping mechanism for each cylinder, an inking mechanism for each cylinder including a distributing part having a plurality of rollers, means for yieldingly holding adjacent rollers in contact, an applying part including a plurality of rollers 90 for applying ink to the design, a conveying part including a roller and means for yieldingly holding said roller in operative relation with both the distributing and applying parts, said holding means including springs constructed and arranged to compensate for variations in the diameters of the rollers, and means whereby the force of the springs may be varied. 100
72. A rotary planographic printing-press including in combination, a plurality of planographic design-cylinders, a damping mechanism for each cylinder, an inking mechanism for each cylinder including a distributing part consisting of a plurality of hard and soft rollers arranged alternately in series, means for yieldingly holding the soft rollers in contact with the adjacent hard rollers, an applying part including a plurality of soft rollers, means for yieldingly holding said rollers in position for applying ink to the design, said holding 110 means including springs constructed and arranged to compensate for variations in the diameters of the rollers, and means whereby the force of the springs may be varied. 115
73. A rotary planographic printing-press including in combination, an impression-cylinder, a planographic design-cylinder, means for moving the design-cylinder into or out of operative relation with the impression-cylinder, a damping mechanism, an inking mechanism including an applying-roller, means for yieldingly holding said applying-roller in operative position, said means including a spring constructed and arranged to compensate for variations in the diameter of the roller, and 120
- 125
- 130

means whereby the force of the spring may be varied.

74. A rotary planographic printing-press, including in combination, an impression mechanism, a plurality of planographic design-cylinders, means for separating and bringing together said impression mechanism and said design-cylinders, a damping mechanism for each design-cylinder, an inking mechanism for each design-cylinder including an applying-roller, means for yieldingly holding said applying-roller in operative position, said holding means including a spring constructed and arranged to compensate for variations in the diameter of the roller, and means whereby the force of the spring may be varied.

75. A rotary planographic printing-press including in combination, an impression mechanism, a plurality of planographic design-cylinders, means for moving the design-cylinders into or out of operative relation with the impression mechanism, a damping mechanism for each design-cylinder, an inking mechanism for each design-cylinder including a plurality of distributing-rollers, means for yieldingly holding said rollers in contact, a plurality of applying-rollers, means for moving the applying-rollers into or out of operative position, means for yieldingly holding the applying-rollers when in operative position, said holding means including springs constructed and arranged to compensate for variations in the diameters of the rollers, and means whereby the force of the springs may be varied.

76. A rotary planographic printing-press including in combination, a planographic design-cylinder, a damping mechanism including applying-rollers, an inking mechanism including applying-rollers, and means whereby the applying-rollers of each of said mechanisms are yieldingly held in operative relation with said design-cylinder, said holding means being constructed to compensate for variations in the diameters of said rollers.

77. A rotary planographic printing-press including in combination, a planographic design-cylinder, a damping mechanism including applying-rollers, an inking mechanism including applying-rollers, means whereby the applying-rollers of each of said mechanisms are yieldingly held in operative relation with said design-cylinder, said holding means being constructed to compensate for variations in the diameters of said rollers.

78. A rotary planographic printing-press including in combination, a planographic design-cylinder, a damping mechanism including applying-rollers, an inking mechanism including applying-rollers, means whereby the applying-rollers of each of said mechanisms are yieldingly held in operative relation with said design-cylinder, said holding means in-

cluding springs constructed and arranged to compensate for variations in the diameters of said rollers, and means for varying the force of said springs.

79. A rotary planographic printing-press including in combination, a plurality of planographic design-cylinders, a damping mechanism for each design-cylinder including applying-rollers, an inking mechanism for each design-cylinder including applying-rollers, and means whereby the applying-rollers of each of said mechanisms are yieldingly held in operative relation with the corresponding design-cylinder, said holding means being constructed to compensate for variations in the diameters of said rollers whereby frequent or accurate individual adjustment of the rollers is rendered unnecessary.

80. A rotary planographic printing-press including in combination, a plurality of planographic design-cylinders, a damping mechanism for each design-cylinder including applying-rollers, an inking mechanism for each design-cylinder including applying-rollers, means whereby the applying-rollers of each of said mechanisms are yieldingly held in operative relation with the corresponding design-cylinder, said holding means including springs constructed and arranged to compensate for variations in the diameters of said rollers, and means for varying the force of said springs.

81. A rotary planographic printing-press including in combination, an impression mechanism, a plurality of planographic design-cylinders, means whereby said design-cylinders and said impression mechanism may be separated and brought together at will, a damping mechanism for each design-cylinder including applying-rollers, an inking mechanism for each design-cylinder including applying-rollers, and means whereby the applying-rollers for each of said mechanisms are yieldingly held in operative relation with the corresponding design-cylinder, said holding means being constructed to compensate for variations in the diameters of said rollers.

82. A rotary planographic printing-press including in combination, a plurality of planographic design-cylinders, a damping mechanism for each design-cylinder including applying-rollers, an inking mechanism for each design-cylinder including applying-rollers, and means whereby the applying-rollers of each of said mechanisms are yieldingly held in operative relation with the corresponding design-cylinder, said damping and inking mechanisms being variously arranged in the press with respect to the action of gravity on the applying-rollers thereof and said holding means being constructed to compensate for variations in the diameters of said rollers and to hold said rollers in their operative positions irrespective of their gravity relations to the design-cylinders.

83. A rotary planographic printing-press including in combination, a plurality of planographic design-cylinders, a plurality of damping mechanisms, and means for moving the water-applying parts of the damping mechanisms about a common center into or out of their operative positions.

84. A rotary planographic printing-press including in combination, a plurality of planographic design-cylinders, a plurality of damping mechanisms, and means for moving the damping mechanisms about a common center into or out of their operative positions.

85. A rotary planographic printing-press including in combination, a plurality of planographic design-cylinders, a plurality of damping mechanisms, a common base to which the water-applying parts of the damping mechanism are secured, and means for actuating said base to move the water-applying parts of the damping mechanisms into or out of their operative positions.

86. A rotary planographic printing-press including in combination, a plurality of planographic design-cylinders, a plurality of damping mechanisms, a common base to which said mechanisms are secured, and means for actuating said base to move the damping mechanisms into or out of their operative positions.

87. A rotary planographic printing-press including in combination, an impression-cylinder, a plurality of planographic design-cylinders, a plurality of damping mechanisms, and means for moving the water-applying parts of said damping mechanisms in a circumferential direction with relation to the impression-cylinder to bring the damping mechanisms into or out of their operative positions.

88. A rotary planographic printing-press including in combination, a planographic design-cylinder, and a self-contained damping mechanism including a water-applying part, a water-distributing part, and driving means for said parts associated therewith and forming a part of the damping mechanism.

89. A rotary planographic printing-press including in combination, a plurality of planographic design-cylinders, a self-contained damping mechanism for each design-cylinder including a water-applying part, a water-distributing part, and driving means for said parts associated therewith and forming a part of the damping mechanism.

90. A rotary planographic printing-press including in combination, an impression-cylinder, a plurality of planographic design-cylinders, a self-contained damping mechanism for each design-cylinder including a water-supplying part, a water-distributing part, and driving means for said parts associated therewith and forming a part of the damping mechanism and means arranged in concentric relation with said impression-cylinder for actuating said driving parts.

91. A rotary planographic printing-press including in combination, an impression mechanism, a plurality of planographic design-cylinders, a self-contained damping mechanism for each design-cylinder including a water-supplying part, a water-distributing part and driving means for said parts associated therewith and forming a part of the damping mechanism, and means for moving the damping mechanisms into or out of their operative positions.

92. A rotary planographic printing-press including in combination, an impression-cylinder, a plurality of planographic design-cylinders, a plurality of self-contained damping mechanisms, each including a water-supplying part, a water-distributing part, and driving means for said parts associated therewith and forming a part of the damping mechanism, means for moving the damping mechanisms into or out of their operative positions, and means common to two or more of said damping mechanisms and arranged concentrically with the impression-cylinder for simultaneously actuating the driving means of said two or more damping mechanisms.

93. A rotary planographic printing-press including in combination, a planographic design-cylinder, a damping mechanism including one or more water-applying rollers adapted to be frictionally driven by the design-cylinder, means for separating or bringing together the design-cylinder and the applying-rollers, and means other than the design-cylinder for driving the said applying-rollers at substantially the surface speed of the design-cylinder when not in contact therewith.

94. A rotary planographic printing-press including in combination, a planographic design-cylinder, a damping mechanism therefor including one or more water-applying rollers adapted to be frictionally driven by the design-cylinder when in contact therewith, means for separating or bringing together the design-cylinder and the applying-rollers, means for driving the applying-rollers when not in contact with the design-cylinder at a slower surface speed than that of the design-cylinder, and means including a slip-clutch for connecting said driving means with the applying-rollers when the latter are not in contact with the design-cylinder.

95. A rotary multicolor planographic printing-press including in combination, an impression mechanism, a plurality of planographic design-cylinders, means for separating or bringing together the design-cylinders and the impression mechanism, a damping mechanism for each design-cylinder, means for moving the damping mechanism into or out of operative relation with the design-cylinders, each of two or more of said damping mechanisms including one or more water-applying rollers adapted to be frictionally driven by the corresponding design-cylinders when

in contact therewith, and means for driving said rollers when not in contact with the design-cylinders.

96. A rotary planographic printing-press including in combination, a plurality of planographic design-cylinders, a damping mechanism for each design-cylinder including an applying-roller, means for separating said design-cylinders and applying-rollers, and means whereby said applying-rollers are yieldingly held in operative position, said holding means being constructed to compensate for variations in the diameters of said rollers and to hold them in operative position irrespective of their gravity relation to the design-cylinders.

97. A rotary planographic printing-press including in combination, a design-cylinder, a damping mechanism therefor comprising a relatively fixed distributing-roller, a water-applying roller, and means for yieldingly supporting said applying-roller whereby contact between the applying-roller and the design-cylinder and the distributing-roller is automatically maintained.

98. A rotary planographic printing-press including in combination, a plurality of design-cylinders, a plurality of damping mechanisms each comprising a distributing-roller and one or more water-applying rollers, means for moving the applying-rollers into or out of operative position and means for yieldingly holding the applying-rollers in operative position whereby contact between the applying-rollers and the design-cylinders and the distributing-rollers is automatically maintained.

99. A rotary planographic printing-press including in combination a planographic design-cylinder, a damping mechanism therefor, means for separating the design-cylinder and damping mechanisms, said damping mechanisms comprising a distributing-roller, a water-applying roller, means for yieldingly holding the water-applying roller in contact with both the design-cylinder and the distributing-roller when the damping mechanism is in operative position, and means for limiting the movement of the applying-roller away from the distributing-roller whereby the applying-roller will remain in contact with the distributing-roller when the design-cylinder and damping mechanism are separated.

100. In a rotary planographic press, a damping mechanism including a fountain and means for supporting said fountain whereby its level may be maintained irrespective of the position of the damping mechanism in the press.

101. In a rotary planographic printing-press, a damping mechanism including in combination a water-fountain roller, a water-fountain, and means whereby said fountain may be adjustably supported in concentric relation with its fountain-roller.

102. A rotary planographic printing-press

including in combination, an impression-cylinder, a plurality of planographic design-cylinders, a plurality of interchangeable damping mechanisms one for each of said design-cylinders, each damping mechanism including a fountain and means for supporting said fountain whereby its level may be maintained irrespective of the position of the damping mechanism in the press.

103. In a rotary planographic printing-press, a damping mechanism including in combination a fountain-roller, a ductor-roller, and a roller between the ductor-roller and the fountain-roller whereby water may be supplied to the ductor-roller from the fountain-roller for various positions of the damping mechanism in the press.

104. A mechanism for supplying liquid comprising a fountain-roller, a driving-disk therefor, a wheel engaged by the face of the disk for driving the same, a shaft for driving said wheel and means for adjusting said wheel longitudinally of said shaft.

105. A mechanism for supplying liquid in graduated quantities comprising a fountain-roller, a driving-disk therefor, and a wheel for driving said disk and adjustable radially thereof.

106. A liquid-supplying device comprising a fountain-roller, a ductor, means for driving the fountain-roller, and means for preventing rotation of the fountain-roller by the momentum or impact of the ductor.

107. A liquid-supplying device comprising a fountain-roller, a ductor, means for driving the fountain-roller, means for moving the ductor into and out of contact therewith, and means consisting of a friction-detent for preventing rotation of the fountain-roller by the momentum or impact of the ductor.

108. A rotary planographic printing-press including in combination, an impression-cylinder, a design-cylinder, damping mechanism, and mechanism including a part common to both the design-cylinder and the damping mechanism and connections normally arranged to move the design-cylinder and the damping mechanism into or out of their operative positions.

109. A rotary planographic printing-press including in combination, an impression-cylinder, a design-cylinder, inking and damping mechanisms, and mechanism including a part common to the design-cylinder and inking and damping mechanisms and connections normally arranged to move the design-cylinder and the inking and damping mechanisms into or out of their respective operative positions.

110. A rotary planographic printing-press including in combination, an impression-cylinder, a design-cylinder, inking and damping mechanisms, and mechanism including a part common to the inking and damping mechanisms and connections normally arranged to

move the inking and damping mechanisms into their respective operative positions in a predetermined sequence.

111. A rotary planographic printing-press including in combination, an impression-cylinder, a design-cylinder, inking and damping mechanisms, and mechanism including a part common to the design-cylinder and the inking and damping mechanisms and connections constructed to move the design-cylinder and the inking and damping mechanisms into their respective operative positions in a predetermined sequence.

112. A rotary planographic printing-press including in combination, an impression mechanism, a plurality of design-cylinders, a plurality of damping mechanisms, and mechanism including a part common to two or more of said design-cylinders and two or more of damping mechanisms and connections normally arranged to move the design-cylinders and the damping mechanisms into or out of their respective operative positions.

113. A rotary planographic printing-press including in combination, an impression mechanism, a plurality of design-cylinders, a plurality of inking and damping mechanisms, and mechanism including a part common to two or more of said design-cylinders, and to two or more of each of said inking and damping mechanisms and connections normally arranged to move the design-cylinders and the inking and damping mechanisms into or out of their respective operative positions.

114. A rotary planographic printing-press including in combination, a plurality of design-cylinders, a plurality of inking and damping mechanisms, an independent driving mechanism for each inking and damping mechanism, and means for actuating said driving mechanisms in unison.

115. A rotary planographic printing-press including in combination, a plurality of de-

sign-cylinders, a plurality of inking and damping mechanisms, means for moving the design-cylinder into or out of operative position, means for separating the design-cylinders and the inking and damping mechanisms, an independent driving mechanism for each inking and damping mechanism and means for actuating said driving mechanisms in unison. 45

116. A rotary planographic printing-press including in combination, a plurality of planographic design-cylinders, a plurality of damping mechanisms, and means including a member common to two or more of said damping mechanisms for yieldingly holding said two or more damping mechanisms in operative relation with their respective design-cylinders. 50

117. A rotary planographic printing-press including in combination, a plurality of planographic design-cylinders, a plurality of damping mechanisms including applying-rollers, means for yieldingly holding two or more of said damping mechanisms in operative relations with the corresponding design-cylinders, and means acting on the applying-rollers individually for yieldingly holding them in contact with the design-cylinders. 55

118. A rotary planographic printing-press including in combination, a planographic design-cylinder, a damping mechanism including a fountain and distributing and applying rollers, means for yieldingly holding the damping mechanism in operative relation with the design-cylinder, and means acting on the applying-rollers individually for yieldingly holding them in contact with the design-cylinder. 60

In testimony whereof I have signed my name to this specification in the presence of two subscribing witnesses.

GEORGE E. PANCOAST.
